Schick Incorporated, Stamford, Conn., a corporation of Delaware

Application August 20, 1942, Serial No. 107,981

Term of patent 14 years

To all whom it may concern:

Be it known that I, Raymond F. Loewy, a citizen of the United States, residing at New York, in the county and State of New York, have invented a new, original, and ornamental Design for a Range Finder, of which the following is a specification, reference being had to the accompanying drawing, forming a part thereof.

Fig. 1 is a perspective view showing the front and right hand side of the instrument;

Fig. 2 is a perspective view showing the front and left hand side of the instrument.

I claim:

The ornamental design for a range finder, as shown.

RAYMOND F. LOEWY.
